UNITED STATES PATENT OFFICE.

CHARLES JOHN BROOKMAN, OF LONDON, ENGLAND.

MEANS FOR DEFINING THE EDGES OF GARDEN PATHS AND FLOWER BEDS.

Application filed January 9, 1926, Serial No. 80,339, and in Great Britain October 1, 1924.

This invention relates to means for defining the edges of garden paths and flower beds.

The object of the invention is to provide 5 an extremely light, neat, effective and durable article which can nevertheless be very cheaply manufactured.

The principal feature of the invention 10 consists in a piece of sheet metal of suitable length and width having at its lower edge suitably spaced integral spurs adapted to be inserted into the ground for fixing the member in position, said sheet metal member being strengthened and rendered capable of 15 being readily bent to conform to any particular shape of path or garden bed by forming corrugations therein.

A further feature consists in connecting 20 a plurality of the sheet metal border members firmly end to end by assembling the end of the upper edge of one member within an overturned bead at the upper edge of the adjoining member.

Other features of the invention are included 25 in the particular construction hereinafter described and set forth in the appended claims.

For the purpose of more fully describing the nature of this invention, reference will 30 now be made to the accompanying drawings, wherein:—

Fig. 1 illustrates in side elevation border members in accordance with this invention in position within the ground.

Fig. 2 is a vertical section on an enlarged scale on line A—A of Fig. 1.

Fig. 3 is a plan view of a portion of a border member also on an enlarged scale.

Fig. 4 is a horizontal section, on an enlarged scale, taken approximately on the line IV—IV of Fig. 1.

In one method of carrying out the invention a piece or strip of suitable sheet metal 1, preferably non-corrodible, of convenient length and width is formed at its lower edge with suitably spaced and preferably V-shaped spurs 2 which are advantageously strengthened by a vertically disposed corrugation 3 extending across the piece of metal 1 from its upper edge to the point of the

spur 2. The upper edge of the metal is curved over upon itself to form a reinforcement or bead 4 which is such that the end of the bead on one section may be inserted into the other to constitute a firm union 55 when, as in use, they are arranged in alignment or end to end, as shown at 6 in Fig. 1.

In use the spurs 2 can be very easily caused to enter the ground, indicated at 5 in Fig. 1, and the corrugations 3 in addition 60 to strengthening the metal enable same to be easily curved or bent to conform to flower beds having round or irregular configuration. To enable the sections to be bent, the beading 4 is kinked as at 4^a at those places 65 opposite the corrugations 3.

The beading 4 may be of substantially tubular formation or same may be formed by merely turning over the edge of the metal so that an inturned or overturned flange 4^b is 70 produced (see Fig. 2) the edge 4^c of which is spaced from the body of the device. The latter arrangement permits of several sections of convenient length being superimposed for compact packing, the inturned 75 flange 4^b of each of the several sections being sprung over the one beneath it, in a similar manner to the overlapping extremities of the border shown at 6 in Fig. 1.

In one convenient method of producing 80 an edging for garden paths, flower beds and the like as herein described, a blank having the spurs 2 is cut or stamped from a sheet of metal of suitable size, the upper edge of which is then turned, by a rolling or other 85 suitable process, to form the beading 4 and the article is completed by stamping or crimping the vertical corrugations which extend from the bottom of the spurs to the beading, as shown.

The upper or beaded edge may be made of ornamental configuration.

The surface of the metal may be ornamented by stamping or other process, and sections thereof, defined by the corrugations, 95 be made to represent a series of tiles.

I claim:—

1. Means for defining the edges of garden paths, flower beds and the like comprising a sheet metal member, an overturned bead 100

formed along the entire length of the upper edge, spaced integral fixing spurs at the lower edge and corrugations extending from the point of each spur to the upper edge of the member.

2. Means for defining the edges of garden paths, flower beds and the like comprising a plurality of sheet metal members, an over-turned bead along the whole length of each

member, said beads being so formed that the end of the bead of one section may be inserted in the end of the bead of the next adjacent section, integral fixing spurs at the lower edge of the members, and corrugations extending upwardly across said members.

CHARLES JOHN BROOKMAN.
